Primary Examiner—T. Chase Nelson*Assistant Examiner*—Karen Acker(74) *Attorney, Agent, or Firm*—Robert K. Roth; Miller, Canfield, Paddock and Stone(57) **CLAIM**

The ornamental design for a fiber optic cable support, as shown and described.

DESCRIPTION

FIG. 1 is a perspective view of a fiber optic cable support shown in accordance with another preferred embodiment.

FIG. 2 is a side view of the fiber optic cable support of FIG. 1.

FIG. 3 is a top view of the fiber optic cable support of FIG. 1.

FIG. 4 is a bottom view of the fiber optic cable support of FIG. 1.

FIG. 5 is a front view of the fiber optic cable support of FIG. 1; and,

FIG. 6 is a back side view of the fiber optic cable support of FIG. 1.

The portions shown in broken line are included for the purpose of illustration only and form no part of the claimed design.
